CIRCUIT FOR STABILIZING FREQUENCIES
OF TRANSMITTER-RECEIVER SYSTEMS

Herbert Reginald Cantele, Writtle, England, assignor to Radio Corporation of America, a corporation of Delaware

Application February 27, 1945, Serial No. 579,994
In Great Britain October 7, 1943Section 1, Public Law 690, August 8, 1946
Patent expires October 7, 1963

18 Claims. (Cl. 250—13)

1

This invention relates to frequency controlling and stabilizing means in radio apparatus and the like, particularly in transmitter-receiver apparatus, that is radio apparatus and the like which may be used either as a transmitter or as a receiver. The invention is particularly suitable for use in such radio apparatus of the kind used for point-to-point operation on a common wave, and provides a means whereby the frequency of the oscillations generated in the apparatus when acting as a transmitter may be stabilized, and whereby the apparatus when acting as a receiver may be maintained in tune with a remote transmitter, in spite of some drift in the frequency of the oscillatory energy transmitted by said transmitter.

Though not exclusively applicable to angular velocity modulated systems, the invention is primarily intended for such systems.

The invention provides a simple means for attaining the control and stabilization of frequency, or of tuning, as the case may be at any frequency within a band covered, or on any spot wave within such band, without recourse having to be had to a variable intermediate frequency.

According to the invention in its widest aspect a radio apparatus, or the like, adapted for use alternatively as a transmitter or as a receiver, includes an oscillation generator and means for automatically stabilizing the transmitter oscillation generator and modulating the frequency of oscillations produced thereby in accordance with signals to be transmitted, when the apparatus is operating as a transmitter, or in accordance with drift in the frequency of received signals, when the apparatus is operating as a receiver.

The invention is illustrated in the drawing whereof Fig. 1 illustrates the first arrangement of the invention, but is not the preferred arrangement, and Fig. 2 illustrates a preferred arrangement. Angular velocity modulation is assumed in both the systems illustrated.

In both figures, O_1 represents an oscillation generator the oscillations from which are to be modulated, CV a reactance modulator or control valve which is subjected to control by, for example, audio frequency signals AF from a source (not shown) and which serves to modulate the oscillations generated in O_1 , M_1 a frequency multiplier to which modulated oscillations are applied, A_1 a power amplifier to which frequency multiplied modulated oscillations are applied, and AT a transmitting aerial to which the output

2

from A_1 is applied. These are the essential elements required for transmission.

Again in both figures, AR represents a receiving aerial, A_2 a radio frequency amplifier to which received energy is applied, FC_3 a frequency changer in which received energy and a beat frequency from FC_2 are mixed to produce an intermediate frequency, IFA an intermediate frequency amplifier to which output from FC_3 is applied, DL a limiter-discriminator to which amplified intermediate frequency is applied and from which the audio frequency signal is derived, A_3 an audio frequency amplifier, the output of which is applied to any suitable utilization device (not shown). These are the essential elements required for reception.

In both figures, O_2 represents a stabilized (for example, crystal controlled) oscillation generator, M_2 a frequency multiplier in which the frequency of oscillations from O_2 is multiplied, FC_2 a frequency changer to which frequency multiplied oscillations from M_1 and M_2 are applied to produce a beat frequency which is applied to frequency changer FC_3 , together with the received radio frequency energy, to produce the intermediate frequency already referred to, FC_4 a frequency changer to which oscillations from O_1 and (in Fig. 1) oscillations from M_2 or (in Fig. 2) a beat frequency from FC_4 are mixed to produce an A. F. C. beat frequency. In Fig. 2, M_3 represents a frequency multiplier in which the frequency of the oscillations generated in O_2 is multiplied or a harmonic selected, O_3 is a stable variable oscillation generator of low frequency, FC_4 is a frequency changer in which oscillations from O_3 and frequency multiplied oscillations from M_3 are mixed to produce a beat frequency for application to FC_1 . These are essential elements for stabilizing the intermediate frequency (output from FC_3) during reception or for stabilizing the frequency of the oscillations generated in O_1 during transmission.

S represents a switch by means of which either the intermediate frequency or the A. F. C. beat frequency may be applied to IFA .

Considering, first, the arrangement of Fig. 1, the operation is as follows:

During transmission the frequency changer FC_4 is excited from the output of the oscillator O_1 and also from the output of the frequency multiplier M_2 . Switch S is on contact T and the difference frequency $O_1 - M_2 \cdot O_2$ is extracted, and used to excite the intermediate frequency amplifier IFA and limiter-discriminator DL . The control valve CV and discriminator circuits DL

are so arranged that a decrease in the frequency of oscillations from O_1 , which results in a decrease in the frequency extracted from FC_1 , produces a bias potential at the limiter discriminator in such sense as, when applied to the control valve, tends to increase and thus restore the frequency of oscillations from O_1 . Similarly the sense of the bias generated when the frequency of oscillations from O_1 increases, is such as to tend to reduce and thus restore the frequency of oscillations from O_1 . The nominal frequency of oscillations of O_1 is made equal to $2 \times M_2 \cdot O_2$, and the mid-intermediate frequency will therefore be $M_2 \cdot O_2$.

For the purpose of reception during which the power amplifier A_1 is switched off at switch S_1 , a portion of the output of the frequency multiplier M_1 together with the output of the frequency multiplier M_2 is used to excite the frequency changer FC_2 , from which the sum frequency $(M_1 \cdot O_1 + M_2 \cdot O_2)$ is extracted. This frequency is then mixed with the incoming frequency in the frequency changer FC_3 and the difference frequency extracted. Switch S is now on the receiver contact R and the signal at this difference frequency is then used to excite IFA . If the receiver and the distant transmitter are exactly in tune the difference frequency at FC_3 will be $(M_1 \cdot O_1 + M_2 \cdot O_2) - M_1 \cdot O_1$ or $M_2 \cdot O_2$. Since this is the mid-frequency of the intermediate frequency amplifier IFA and limiter no frequency correcting bias will be generated by DL . If, however, the frequency of the incoming signal decreases, the difference frequency extracted from FC_3 will increase and therefore produce from discriminator DL a bias which will tend to decrease the frequency of oscillation of O_1 , and therefore also of the frequency multiplier M_1 . The frequency extracted from the frequency changer FC_3 thus tends to remain constant, even if the incoming signal should drift in frequency. In systems employing a narrow deviation band it is especially important in order to avoid distortion arising in the detection of the signal by the discriminator and its rectifier that the mean frequency applied to the discriminator should remain substantially constant. The circuit means provided permit this end to be achieved.

The simple scheme described does not readily lend itself to the second object of the invention viz., the stabilization of the transmitter oscillator at any frequency within its band, as it provides only for frequency stabilization at one spot frequency of the transmitter oscillator. It is moreover subject to the disadvantage that the output circuit of the frequency changer FC_1 is tuned to the same frequency as the output circuit of the frequency multiplier M_2 . The output circuit of the frequency changer FC_1 will therefore contain two components of the same frequency, one derived from the frequency changing action and one arising from direct amplification of the frequency $M_2 \cdot O_2$. Since the limiter discriminator DL will respond to the larger of the two signals it is necessary to make the component due to direct amplification of $M_2 \cdot O_2$ small in relation to that due to frequency changing action, and this may be a matter of some difficulty to arrange. Accordingly the slightly more complicated circuit arrangement shown in Fig. 2 is preferred. This incorporates all the elements of Fig. 1 and the necessary additional elements. The frequency of the stable variable oscillator O_3 , which is of low frequency, may be determined either by an L. C. circuit or by a CR circuit. The range of

frequency variation of the variable oscillator is chosen to be equal to the frequency of the crystal oscillator O_2 . The frequency multiplier M_3 selects one of the higher order harmonics of the crystal oscillator O_2 . The output frequency of the variable oscillator O_3 is mixed with the output frequency of the multiplier M_3 in the frequency changer FC_4 from which, as may be convenient, the sum or the difference of the two frequencies may be extracted. This extracted frequency $M_3 \cdot O_2 \pm O_3$ is the reference frequency used for the stabilization of O_1 . Since the intermediate frequency and the frequency to which the discriminator is tuned are constant it can be seen that for any value of the frequency of O_1 , provided the frequencies of O_2 and O_3 are suitably chosen, a suitable harmonic of the crystal oscillator may be combined with a suitable value of the frequency of the oscillator O_3 to give a frequency which differs from the frequency of the oscillator O_1 by a constant amount equal to the intermediate frequency. Thus, for example, let it be assumed that the intermediate frequency is 4 mc./s. and that the oscillator O_1 is to be tunable over the range of 15 to 24 mc./s. Let it also be assumed that the frequency of O_2 is 1 mc./s. and that the harmonic selector M_3 permits the selection of harmonics from the 10th to the 18th. Assuming that the sum of the frequencies $(O_3 + M_3 \cdot O_2)$ is extracted from FC_4 it can readily be seen that the frequency range to be covered by O_3 is from 1 to 2 mc./s. Thus with O_1 at 15 mc./s., $M_3 \cdot O_2$ will be 10 mc./s., $(M_3 \cdot O_2 + O_3)$ will be 11 mc./s., and the difference $O_1 - (M_3 \cdot O_2 + O_3)$ will be 4 mc./s. With O_1 at 24 mc./s., $M_3 \cdot O_2$ will be 18 mc./s., and O_3 will be 2 mc./s., so that $O_1 - (M_3 \cdot O_2 + O_3) = 24 - (18 + 2) = 4$ mc./s. For some odd value of the frequency of O_1 , say, 18.75 mc./s., $M_3 \cdot O_2$ will be 13 mc./s., and O_3 will be 1.75 mc./s., so that

$$O_1 - (M_3 \cdot O_2 + O_3) = 18.75 - (13 + 1.75) = 4 \text{ mc./s.}$$

Alternatively, if continuous variation of O_1 is not required, but merely a selection of spot waves, O_3 may be a crystal oscillator having a harmonic selector covering any desired number of harmonics over a range of the frequencies equal to the frequency of O_2 . It will thus act as a vernier to O_2 . If a few spot waves only are required O_3 and FC_4 may be omitted and the output of M_3 be fed directly to FC_1 .

The frequency multiplier M_2 is of fixed frequency, and selects a harmonic of O_2 equal to the intermediate frequency. The frequency changer FC_2 is tuned to a frequency

$$(M_1 \cdot O_1 + M_2 \cdot O_2)$$

as in the case of Fig. 1. The frequency O_1 is not in this circuit embodiment restricted in its relation to $M_2 \cdot O_2$.

Since the frequency of O_3 is small in relation to the harmonic frequency $M_3 \cdot O_2$, with which it is combined, a small percentage drift in O_3 will represent a much smaller percentage drift in the combined frequency $(O_3 + M_3 \cdot O_2)$ and will therefore have negligible effect on the stability of the system.

An advantage of the system in both the simple and preferred arrangements is that the output of the frequency multiplier M_2 may, by suitable switching, be used for the purpose of alignment of the intermediate frequency stages, without the use of an external source of frequency.

What is claimed is:

1. A radio or like apparatus adapted for use

alternatively as a transmitter or as a receiver, including an oscillation generator for producing oscillations for modulation and ultimate transmission, a frequency changer for producing an intermediate frequency from received signal frequency and oscillations derived from said oscillation generator, means for producing a first frequency controlling potential variable in sign and magnitude in accordance with departures from a desired frequency of the output from said generator, means for producing a second frequency controlling potential variable in sign and magnitude in accordance with departures from the frequency of received signal frequency requisite to maintain a desired mean frequency of said intermediate frequency, a frequency controlling device for said oscillation generator operable under control of said first frequency controlling potential to stabilize the frequency of said generator or under control of said second frequency controlling potential to vary the frequency of said generator, thereby to stabilize said intermediate frequency.

2. Apparatus as claimed in claim 1, including a stabilized oscillation generator and a second frequency changer and wherein said first frequency controlling potential is derived from a first frequency controlling beat frequency produced by mixing oscillations derived from both said generators in said second frequency changer coupled thereto and to said first oscillation generator.

3. Apparatus as claimed in claim 1, including a stabilized oscillator generator, a second frequency changer coupled thereto and to said first oscillation generator, a coupling between said second frequency changer and said first frequency changer and wherein said second frequency controlling potential is derived from said intermediate frequency and wherein said intermediate frequency is produced by mixing a second frequency controlling beat frequency with said received signal frequency in said first frequency changer, said second frequency controlling beat frequency being produced by mixing oscillations derived from both said generators in said second frequency changer.

4. A radio or like apparatus adapted for use alternatively as a transmitter or as a receiver and having a first oscillation generator, means for modulating oscillations from said generator in accordance with signals to be transmitted, means for transmitting modulated oscillations, and means for receiving oscillatory energy from a remote station including, for use when said apparatus is operating as a transmitter, a second oscillation generator, means for deriving a first automatic frequency controlling beat frequency from oscillations generated by both said generators, means for deriving a first automatic frequency controlling potential from said first automatic frequency controlling beat frequency and means for applying said potential to said first generator so as to maintain the frequency of oscillations generated thereby substantially constant, and, for use when said apparatus is operating as a receiver, said second oscillation generator, means for deriving a second automatic frequency controlling beat frequency from oscillations generated by both said generators, means for deriving an intermediate frequency from said second automatic frequency controlling beat frequency and said received oscillatory energy, means for deriving a second automatic frequency controlling potential from said intermediate frequency, and means for applying said potential

to said first generator so as to vary the frequency of the oscillations generated thereby, thus by varying the frequency of said second automatic frequency controlling beat frequency, to maintain said intermediate frequency substantially constant in spite of drifts in the frequency of said received oscillatory energy.

5. A radio or like apparatus adapted for use alternatively as a transmitter or as a receiver and having a first oscillation generator, means for modulating oscillations from said generator in accordance with signals to be transmitted, means for transmitting modulated oscillations, and means for receiving oscillatory energy from a remote station including, for use when said apparatus is operating as a transmitter, a first stabilized oscillation generator, a second stabilized, variable, oscillation generator, means for deriving a stable beat frequency from oscillations generated by both said stabilized oscillation generators, means for deriving a first automatic frequency controlling beat frequency from said stable beat frequency and oscillations from said first generator, means for deriving a first automatic frequency controlling potential from said first automatic frequency controlling beat frequency, and means for applying said potential to said first generator so as to maintain the frequency of oscillations generated thereby substantially constant, and, for use when said apparatus is operating as a receiver, said first stabilized oscillation generator, means for deriving a second automatic frequency controlling beat frequency from oscillations generated by said first and first stabilized oscillation generators, means for deriving an intermediate frequency from said second automatic frequency controlling beat frequency and said received oscillatory energy, means for deriving a second automatic frequency controlling potential from said intermediate frequency, and means for applying said potential to said first generator so as to vary the frequency of the oscillations generated thereby thus, by varying the frequency of said second frequency controlling beat frequency, to maintain said intermediate frequency substantially constant in spite of drifts in the frequency of said received oscillatory energy.

6. Apparatus as claimed in claim 4, wherein the modulated oscillations are subjected to frequency multiplication before transmission and the first beat frequency is derived from the mixing of oscillations from the first generator without frequency multiplication with oscillations from said second generator.

7. Apparatus as claimed in claim 5, wherein the modulated oscillations are subjected to frequency multiplication before transmission and the first automatic frequency controlling beat frequency is derived from the mixing of oscillations from the first generator without frequency multiplication with the stabilized beat frequency.

8. Apparatus as recited in claim 1 including a stabilized oscillation generator, a frequency increaser coupled therewith wherein oscillations produced by said stabilized oscillation generator are subject to frequency multiplication and harmonic selection, said first means comprising a frequency changer coupled to said first oscillation generator and said frequency increaser wherein oscillations from said first mentioned oscillation generator are mixed with oscillations from said frequency increaser for the production of energy of beat frequency from which said first frequency controlling potential is derived.

9. Apparatus as recited in claim 1 including a stabilized oscillation generator, a first frequency increaser coupled to said first oscillation generator, a second frequency increaser coupled to said stabilized oscillation generator, and wherein said second means includes a frequency changer coupled to both of said frequency increasers to produce a frequency controlling beat note used in said second means for producing said second frequency controlling potential.

10. Apparatus as recited in claim 1 including a stabilized oscillation generator and a stabilized variable frequency oscillation generator, a frequency changer coupled with said last two generators for producing energy of a beat frequency and of constant frequency, and wherein said first means includes a frequency changer coupled with said last named frequency changer and with said first oscillation generator for producing energy of a second frequency controlling beat frequency from which said first frequency controlling potential is derived.

11. Apparatus as recited in claim 1 including a stabilized oscillation generator, a second frequency changer coupled to said stabilized oscillation generator and to said first oscillation generator for deriving energy of frequency controlling beat frequency, and wherein said second means includes a coupling between said second frequency changer and said first frequency changer which is excited by received signals for producing energy of a second frequency controlling beat frequency from which is derived said second frequency controlling potential.

12. Apparatus as recited in claim 1 including a stabilized oscillation generator, a second frequency changer coupled therewith and with said first named oscillation generator, a frequency multiplier in each of said last two named couplings, and wherein said second named means includes a coupling between said second frequency changer and said first named frequency changer which is excited by received signals for producing energy of a frequency controlling beat frequency from which said second mentioned frequency controlling potential is derived.

13. Apparatus as recited in claim 1 including a source of signals and a coupling between said source of signals and said frequency controlling device for modulating the oscillations generated by said first generator in accordance with signals.

14. Apparatus as recited in claim 1 wherein said first and second means includes a frequency discriminator and detector which produces said first and second control potentials and also serves as a detector of frequency modulation on the received wave.

15. Apparatus as recited in claim 4 including a frequency multiplier coupled to said first oscillation generator in which multiplier the modulated

oscillations are subject to frequency multiplication before transmission, a second frequency multiplier coupled to said second oscillator, said third means including a frequency changer coupled to said modulated oscillator and to said second frequency multiplier so that said first automatic frequency controlling beat frequency is derived by mixing oscillations from said second generator multiplied in frequency with oscillations from said first oscillation generator.

16. Apparatus as recited in claim 4 including a frequency multiplier coupled to said modulated oscillation generator, a frequency multiplier coupled to said second oscillation generator and wherein said means for deriving said second automatic frequency controlling beat frequency includes a frequency changer coupled to both of said frequency multipliers.

17. Apparatus as recited in claim 5 including a frequency multiplier coupled to said modulated oscillation generator to subject the modulated oscillations to frequency multiplication before transmission, a second frequency multiplier coupled to said first stabilized oscillation generator, and wherein said fourth means includes a frequency changer coupled to said last mentioned frequency multiplier and to said second stabilized oscillation generator for deriving said first stabilized beat frequency.

18. Apparatus as recited in claim 5 wherein said means for deriving said second automatic frequency controlling beat frequency includes a frequency changer and frequency multipliers coupling said first stabilized oscillation generator and said first oscillation generator to said frequency changer wherein is derived said second automatic frequency controlling beat frequency.
